UNITED STATES PATENT OFFICE.

HENRY M. VAUGHAN, OF NEWTON, IOWA.

WASHING MACHINE.

Application filed December 21, 1922. Serial No. 608,291.

To all whom it may concern:

Be it known that I, HENRY M. VAUGHAN, a citizen of the United States of America, and a resident of Newton, Jasper county, 5 Iowa, have invented certain new and useful Improvements in Washing Machines, of which the following is a specification.

My invention relates to improvements in washing machines, and the object of my 10 improvement is to supply an oscillatory rubbing element within the tub of a washing machine provided with cleats which are undercut or grooved in such a manner as to most effectively agitate the contents of the 15 tub in the operation of the machine, thus more rapidly and thoroughly cleansing the contents.

This object I have accomplished by the means which are hereinafter described and 20 claimed, and which are illustrated in the accompanying drawings, in which Fig. 1 is a perspective elevation of a washing machine tub equipped with my improved rubbing disk, the hinged cover and disk being in 25 opened positions, but the operating mechanism for the disk being removed. Figs 2 and 3 are like under plan views of the cleated rubbing disk in slightly different arrangements of the cleats, and Fig. 4 is a 30 cross section of one of the longitudinally and laterally grooved rubbing cleats. Fig. 5 is a section of part of said disk taken through one of the holes 2.

The washing machine tub 7, its hinged 35 cover 8, the oscillatory rubbing disk 1 with its rock-shaft 9 traversing the cover 8 are of the usual type, and any appropriate or convenient mechanism or motive power therefor may be employed to rock the shaft 9 40 and disk 1, as may be desired.

The disk 1 may have a plurality of holes 2 to provide a ready circulation of water through the disk during the operation of the machine, but these are not essential to the 45 special action upon the clothes contents of the tub of the depending rubbing cleats 3, 4 and 5 fixed on the lower face of said disk. The disk 1 may be of any other suitable configuration and it is also the cleats may be 50 of any desired size, relative arrangement and forms, while coming within the scope of my invention, which is the hollowing or undercutting or longitudinally and laterally grooving the cleats for the purpose herein- 55 after described.

My preferred relative arrangement or po-

sitioning of said cleats, is to have them secured to the disk 1 radially.

The grooving or hollowing of certain of the cleats may be along either side thereof 60 longitudinally. As shown, each grooved cleat may have a cross-sectional form illustrated in Fig. 4, the cleat being an elongated rib, apically rounded, with a reentrant groove 6 extending along one side longitudinally.

As shown in Fig. 2, an ungrooved diametrical rib 3 may be positioned across the under face of the disk 1, and several shorter radial and diametrically spaced grooved 70 cleats or ribs 4 and 5 positioned at opposite sides of this rib or cleat 3. While the grooves 6 on the shorter radial cleats may open in the same direction, I have found the arrangement shown more efficient, where the 75 grooves 6 along one set of ribs 4 open oppositely to the grooves on the other set of ribs or cleats 5. This is because when the disk 1 is oscillated to and fro, the grooves 6 in one set of cleats 4 engage and rub the 80 clothes more than the smooth sides thereof and agitate the water while moving in one direction, and when the disk is rocked back, the grooves 6 in the other cleats 5 reverse the 85 rubbing and agitating effect upon the clothes and water in the tub quickly and with more cleansing effect upon the clothes and in causing better circulation of the water. The 90 grooves receive and carry along portions of the water and the clothes, thereby spreading 95 and opening out the folds of the clothes and driving the soapy water through them with force.

As shown in Fig. 3, the diametrical cleat 3' is made in spaced aligned sections, and the 95 function of this diametrical cleat in either shape is to act as a barrier to prevent entangling of the clothes in the reversal of the disk, while better localizing the effect of the grooved walls of the particular cleats at one 100 side of the cleat 3.

The dotted circles about and concentric with the holes 2 in the disk 1 indicate that the holes are of conical shape, with their smaller openings on the lower or cleat-bearing face of the disk. The conical holes afford quicker passage to water than the ordinary cylindrical holes.

Having described my invention, what I claim as new, and desire to secure by Letters Patent, is:

1. In a washing machine, a tub, an oscilla-

tory body positioned therein and having projecting parts which are grooved along one side only, the grooves on these parts on one part of said body opening oppositely to the like grooves on the opposite part of said body to engage the contents of the tub when the body is rocked in either of opposite directions.

2. In a washing machine, a tub, an oscillatory body positioned therein, and radial

cleats secured upon said body, certain of said cleats being grooved along one side, and the said grooved cleats being segregated into groups in which the grooves in one group face oppositely from the grooves in another group. ¹⁵

Signed at Newton, Iowa, this 25th day of November, 1922.

HENRY M. VAUGHAN.
